US00D794071S

(12) **United States Design Patent** (10) Patent No.: **US D794,071 S**
(45) Date of Patent: ** Aug. 8, 2017

(54) **DISPLAY SCREEN OR PORTION THEREOF WITH ICON**

(71) Applicant: **Samsung Electronics Co., Ltd.**, Suwon-si, Gyeonggi-do (KR)

(72) Inventors: **Minsun Kim**, Seongnam-si (KR); **Hyunjung Kwon**, Seoul (KR); **Heyungjoo Kim**, Seoul (KR)

(73) Assignee: **SAMSUNG ELECTRONICS CO., LTD.**, Gyeonggi-Do (KR)

(**) Term: **15 Years**

(21) Appl. No.: **29/559,663**

(22) Filed: **Mar. 30, 2016**

(30) **Foreign Application Priority Data**

Oct. 1, 2015 (KR) 30-2015-0049569

(51) LOC (10) Cl. **14-04**

(52) U.S. Cl.

USPC **D14/492**

(58) **Field of Classification Search**

USPC D14/485-495

CPC .. G06F 3/0481; G06F 3/04817; H04N 21/478

See application file for complete search history.
